UNITED STATES PATENT OFFICE.

WILLIAM R. HOWE, OF DAYTON, OHIO.

ELASTIC-TREAD HORSESHOE.

SPECIFICATION forming part of Letters Patent No. 530,528, dated December 11, 1894.

Application filed January 22, 1894. Serial No. 497,688. (No model.)

To all whom it may concern:

Be it known that I, WILLIAM R. HOWE, a citizen of the United States, residing at Dayton, in the county of Montgomery and State 5 of Ohio, have invented certain new and useful Improvements in Horseshoes, of which the following is a full, clear, and exact description, reference being had to the accompanying drawings, forming part of this specification.

My invention relates to that class of horse-shoes in which there is a recess in the under side to receive elastic material to prevent shocks and jars and keep the horse from slipping, and it has for its object the improved 15 construction of such shoes whereby their durability and efficiency are increased.

The novelty of my invention will be hereinafter set forth and specifically pointed out 20 in the claims.

In the accompanying drawings:—Figure 1 is a bottom plan view of a horse-shoe embodying my invention. Fig. 2 is a transverse section of the same on the dotted line $x-x$ of 25 Fig. 1. Fig. 3 is a longitudinal section on the dotted line $y-y$ of Fig. 1.

The same letters of reference are used to indicate identical parts in all the figures.

A is the body of the shoe of the usual or 30 any suitable construction made of iron or any other metal and with a groove a , rectangular in cross section, on its under side extending entirely around it. At the toe, the front wall of the groove is cut away or dispensed with, leaving an opening b into the 35 groove.

Fitted within the groove so as to fill the same and projecting slightly beyond the metal of the bottom of the shoe is an elastic 40 packing B which may be of soft vulcanized rubber or any other suitable material possessing its characteristics of elasticity and adhesion on wet or slippery surfaces. This packing not only fills the groove but also the opening 45 in the front wall at b and comes flush with the end of the toe. When the packing is of rubber that part of the same at the toe-opening is made harder than the rest so as to better resist wear.

50 I prefer to slightly incline or dovetail the rear wall of the groove directly behind the

toe opening as shown in Fig. 3, and also the side walls at the toe, as indicated by the dotted lines in Figs. 1 and 2, to aid in holding the packing in place; and to secure it 55 permanently I provide a wire c which is strung through a perforation in the packing and passes out through perforations in the heel of the shoe. This wire is drawn tight and its ends are bent over or clinched against 60 the heel of the shoe as seen in Fig. 1. In this simple but efficient manner the packing is secured in place, and a shoe thus constructed not only combines the metallic and elastic non-slipping wearing surfaces which 65 will wear equally and prolong the life of the shoe, but it also provides what has never before been provided in shoes of this character, namely, a hardened elastic non-slipping toe piece, for, as is well known, horses in lifting 70 their feet always tilt them on the toe to get a purchase in moving forward, and by my construction this toe is composed wholly of the hardened elastic non-slipping material.

By inclining or beveling the rear wall of 75 the groove at the toe, as seen in Fig. 3, it will be observed that the wire C in addition to its function of holding all of the elastic packing in place also exerts a pressure which forces the hardened portion in the toe-opening 80 tight up against the metal of the shoe, a tilting action being given to the rubber owing to the bevel of the wall which makes a tight joint and prevents sand or dirt from getting in between the metal and packing at the toe 85 opening.

Having thus fully described my invention, I claim—

1. In a horse-shoe, the combination of the metal body having a continuous groove on its 90 under side with its front wall at the toe cut away and its rear wall at the toe beveled, an elastic packing fitted or seated in said groove and toe-opening, and a retaining wire threaded through the packing its entire 95 length and secured at its ends to the metal body, whereby said wire serves to hold said packing in place and exerts an upward pressure on the packing at the toe-opening, substantially as described. 100

2. In a horse-shoe, the combination of the metal body having a continuous groove on its

under side with an opening in its front wall at the toe, and an elastic packing fitting and secured in said groove and toe opening, substantially as described.

5. 3. In a horse-shoe, the combination of the metal body having a continuous groove on its under side with an opening in its front wall at the toe, and an elastic vulcanized rubber

packing fitting and secured in said groove and toe opening, and with that portion in the toe opening made harder than the rest, substantially as described.

WILLIAM R. HOWE.
